UNITED STATES PATENT OFFICE.

EDWARD H. BELDEN, OF PITTSBURGH, PENNSYLVANIA.

INTERNAL-COMBUSTION ENGINE.

1,017,074.

Specification of Letters Patent. Patented Feb. 13, 1912.

Application filed November 9, 1911. Serial No. 659,441.

To all whom it may concern:

Be it known that I, EDWARD H. BELDEN, a citizen of the United States, and a resident of Pittsburgh, county of Allegheny, and 5 State of Pennsylvania, have invented certain new and useful Improvements in Internal-Combustion Engines, of which the following is a specification.

My invention relates to internal combustion engines and has particular reference to 10 improvements in the valves and valve gearing of internal combustion engines of the four-cycle type.

The objects of my invention are to simplify the construction and to lessen the cost 15 of such engines; to eliminate the vibration and the noise incident to their operation; to balance the valves thereof; and, to increase the power efficiency and durability 20 thereof.

My further purpose is to do away with the short-lived and noisy reciprocating valves and valve gearing now in common use and to substitute therefor a minimum 25 number of large substantial parts that cannot easily be broken, to balance the valves and otherwise arrange and construct them to offer the least possible resistance to the operation of the engine.

30 A special object of my invention is to provide an engine of the class named with a non-vibratory, constantly lubricated and substantially balanced admission and exhaust valve and to maintain it at a low temperature protected from the hot gases of the cylinder.

Still other objects of the invention are to provide an internal combustion engine equipped with a balanced valve and having 40 a cylinder which contains both the cylinder head and the necessary port-controlling means and from which both the head and the piston may be removed without disturbing the cylinder or said portcontrolling means 45 or gearing, and from which the valve may be removed without disturbing the cylinder or the valve gearing; and to provide an engine having valves and valve seats which shall be freely accessible upon removal of 50 the cylinder head.

Another object of my invention is to provide a four-cycle engine, as outlined above, that may be made and assembled, dis-

membered and reassembled by ordinary mechanics and in less time than other four- 55 cycle engines.

A further object is to provide balanced rotary valves and valve gearing of such form and arrangement that the several cylinders of a multiple engine may be economically 60 formed in one block or casting.

Still further objects of my invention will appear hereinafter.

My invention resides in an internal combustion engine wherein the foregoing objects are attained, the same embodying the principles and being of the general construction and combination of parts hereinafter described and particularly pointed out in the appended claims. 70

The invention will be readily understood upon reference to the accompanying drawings, which form part of this specification and in which I have depicted a preferred embodiment of my invention in a six cylinder internal combustion engine. 75

In the drawings, Figure 1 is a side elevation of my novel engine, four of the cylinders being shown in vertical longitudinal section;—Fig. 2 is a horizontal section, substantially on the line 2^x—2^x of Fig. 1, all of the cylinder heads being removed;—Fig. 3 is an enlarged vertical section on the line 3^x—3^x of Figs. 1 and 4, disclosing the means for balancing the valve;—and, Fig. 4 is a horizontal section on the line 4^x—4^x of Fig. 3. 80

I have here illustrated my invention as embodied in a water cooled multiple cylinder engine of a vertical type particularly 90 adapted for use in automobiles. Its cylinders A, six in number, are arranged side by side in a single casting B. Various means may be employed for cooling the cylinder and valve seats. For example the casting 95 B may contain a water space or jacket C which is common to all the cylinders. The water space extends from the top B' of the casting to a point near the lower ends of the cylinders. The bottom B'' of the cylinder 100 casting is secured upon the top of the base D. The base contains the crank shaft E shown in dotted lines in Fig. 1. On one end of the shaft E is a fly wheel F. The other end of the crank shaft carries a 105 sprocket wheel G, (see dotted lines Fig. 1.)

the use of which will be explained herein-after. Each cylinder A contains a piston H, joined to the crank shaft E by a connecting rod I, shown in dotted lines in Fig. 5. 1. The cylinders open through both the top and the bottom of the casting B. They have separate heads J. The head J of each cylinder is preferably wholly contained within the upper or outer end of the cylinder. I 10 make these ends of the cylinders large enough to receive the pistons so that the latter may be inserted and removed through the tops of the cylinders after the cylinder casting B has been fastened to the base D. 15 The heads are larger than the pistons and each head rests upon an annular shoulder a^2 , which distinguishes the piston containing portion a^3 of the cylinder from its head containing portion a^4 . Both cylinder portions a^3 and a^4 are cylindrical. They are 20 preferably concentric. The portion a^4 is large enough to contain not only the head but also the valve K, about to be described. Each head has an annular flange J' that fits 25 the upper part of the cylindrical bore a^4 . The lower end J^2 of each head J snugly fits the piston bore a^3 of the cylinder and the annular shoulder J^3 of the head rests upon the cylinder shoulder a^2 as before explained. 30 The upper end of the bore a^4 of each cylinder is threaded to receive a locking ring L, which is screwed firmly upon the flanged top of the head, completing an oil and pressure tight joint between the head and the 35 cylinder at that point. If desired, a key or set screw L' may be added to lock the head against rotation; such device, however, is not essential to the fastening of the head in the cylinder. The shoulder a^2 of the cylinder and the shoulder J^3 of the head are 40 ground together and when the head is thus secured the shoulders form an oil and pressure tight joint between the lower end of the head and the cylinder. It will be observed 45 that the concentricity of the cylinder and the head is insured by the close fitting of the upper end and the lower end of the head within the larger and the smaller bores a^4 and a^3 of the cylinder. The intermediate 50 portion of each head J, between the flange J' and the shoulder J^3 , is cylindrical and concentric with the containing bore a^4 . While this portion, as herein shown, is larger than the piston bore a^3 , it is somewhat 55 smaller than the bore a^4 and an annular cavity K' having parallel cylindrical walls is therefore formed between the cylinder and the head. The top of the cavity K' is formed by the underside of the head 60 flange J'. The bottom of the annular cavity is formed by the cylinder shoulder a^2 on which the head rests. All of the walls of the cavity are finely ground and serve as seats for the valve K before referred to.

The valves K are simple one-piece sleeves 65 or rings that exactly fit their respective cavities K'. They are interchangeable. The inner and outer surfaces of each valve K are finely ground and cylindrical and parallel. The top and bottom edges are also 70 finely ground or finished and are parallel and perpendicular to the cylindrical surfaces. In practice, the cross sectional dimensions of the valve K are approximately two thousandths of an inch smaller than the 75 corresponding dimensions of the cavity K', leaving space for thin films of oil between all the opposed surfaces of the valve, cylinder and head. Obviously the space is increased at the groove K^x and between the 80 gear teeth on the valve. Each valve K contains at least one opening or port K², the same being of sufficient size to quickly admit and to quickly free the gases and being positioned about midway of the height of the 85 valve. As shown in the drawings I prefer to provide each valve with two diametrically opposite ports K², so that one revolution of the valve shall serve for eight successive strokes, two complete power operations, of the piston, as hereinafter explained. Each cylinder is provided with an admission port and passage A⁴ and an exhaust port and passage E, these being formed in the casting B. The ports A⁴ and E^x open into 90 respective valve cavities K' in position to register with the ports K² in the valve K. The width of the space between the inlet and exhaust ports approximately equals the width of the port K² in the valve K. These 95 dimensions may be considerably varied without departing from the invention but I prefer to maintain the described proportions and relation for the particular reason that after the valve has opened to permit the 100 heated gases to exhaust, those portions of the valve which are heated by the exhaust gases are almost immediately cooled by the inrush of cool combustible mixture at the port A⁴. The time between the exhaust and 105 the admission of mixture is proportionate to the distance that the valve has to travel between the ports E^x and A⁴. In a multiple cylinder engine I prefer to pair the cylinders and connect the exhaust passages E^x of 110 each pair as shown in Figs. 2 and 4. From the points of juncture the exhaust passages extend downward and open through the lower part of the casting B.

E^{x2} represents the vertical extension of 120 the united exhaust ports of two cylinders.

E^{x2} represents the exhaust manifold of the engine. As indicated in Fig. 2 I prefer that the admission passages A⁴ of the several cylinders shall be independent 125 and shall open through the outer face of the casting above the exhaust manifold. The passages A⁴ are connected by an ad-

mission manifold A^{d2} having two connections A^{d3} and A^{d4} with a suitable carburetor A^{d5} . As best shown in Figs. 3 and 4, each head J contains a central cavity J^4 hemispherical at the top and opening through the bottom of the head. This cavity which obviously communicates with the piston containing portion a^2 of the cylinder constitutes the compression and combustion chamber of the engine. A central hole is provided in the top of the head and in this hole is the device M for igniting the gases, preferably an electric spark plug. Two passages $J-A^d$ and $J-E^x$ are formed in the head. These open through the valve seat surface of the head, at points directly and respectively opposite the ports A^d and E^x in the valve seat surface of the cylinder, hence these passages or ports of the head are in position to register with the ports K^2 in the valve K . The head J contains still another passage, virtually a cavity; namely the valve balancing passage or cavity JB which extends from the central cavity J^4 of the head through the valve seat surface of the head. This opening JB in the head is approximately opposite the ports $J-A^d$ and $J-E^x$. At times when the latter are closed by one side of the valve, the port JB is also closed by the opposite side of the valve. The arrangement is such that one port K^2 of the valve registers with the head port or cavity JB at times when the other port K^2 in the valve is passing the ports A^d , $J-A^d$ and E^x , $J-E^x$ in the cylinder and head. The area of the port JB in the head is preferably slightly less than the combined area of the admission and exhaust ports A^d and E^x in the cylinder. The practical effect of this arrangement of the valve and ports is that the revoluble valve is so nearly balanced in its cavity that it is but lightly seated across the cylinder ports A^d and E^x , even at the moment of maximum pressure within the cylinder. In consequence, the valve is not permitted to cling upon any of its seats and it is not difficult to turn or rotate it in its cavity. At the same time, it will be noted that at moments of vacuum within the cylinder, as when the piston is descending and the admission port A^d and the valve port K^2 are in register, the area of the balancing port JB exceeds the area of the exhaust port in the cylinder, with the result that there is an overbalancing external pressure on the valve which tightly holds it over the exhaust port E^x in the cylinder and prevents the indraft of gases from the exhaust passage E^x .

60 The valve operating mechanism is most clearly shown in Figs 1, 2, 3 and 4. Each member K is a combined valve and gear wheel; that is, the lower outer edge of each valve K is provided with gear teeth K^3 constituting an integral gear wheel whereby the valve may be rotated in its valve chamber or cavity. The valve operating member is arranged on the side of the engine opposite the side which contains the several admission and exhaust ports. This valve operating member comprises a single shaft N having as many integral gear wheel portions N' as there are valves. Each cylinder is provided with an opening AN , at a point opposite the gear teeth on the valve and considerably below the level of the ports K^2 in the valve. This opening admits the operating gear N' into mesh with the gear teeth upon the valve. Obviously all of the openings AN are arranged in a horizontal line. The shaft N is held in suitable bearings N^2 provided on the side of the cylinder casting B as shown in Figs. 2 and 4. The gear teeth on the valves and on the shaft N are preferably forty-five degree spiral teeth. Such gears operate readily in either direction and are noiseless. At its end, the shaft N is provided with a sprocket wheel N^3 and this is connected with the sprocket wheel G on the crank shaft by a suitable sprocket chain G^a . The sprockets G and N^3 , and the sprocket belt G^a constitute the driver for the valve operating member or shaft N . The rotation of the crank shaft is thereby communicated to the several valves, and the latter are rotated constantly during the operation of the crank shaft. The sprockets G and N^3 and the gears N' and K^3 are so proportioned that the valves are caused to turn one-half of a revolution during each two revolutions of the crank shaft. It will be clear that the rotative speed of the valves is relatively low and that nothing short of the breakage of one of these heavy substantial parts can interfere with the proper action of the valve. The valve operating shaft and gears are contained by a horizontal duct O formed in the side of the cylinder casting.

65 B^4 , B^5 are the edges of the duct O . These edges are integral with the cylinder casting B . The opening between them is closed by a horizontal plate B^5 tightly bolted thereto and making the duct oil tight. The duct O and the several valve cavities are in communication through the openings AN . The sprockets G and N^3 and sprocket belt G^a are inclosed by a casing P , the upper end of which communicates with the duct O and the lower end of which communicates with the interior of the engine base D . An oil pump (not shown) forces oil into the duct O . The oil is distributed therefrom to the several valves by the gear wheels N' and K^3 . In the case of each valve, its rotation causes the oil to spread upon the outer surface of the valve whence it will work above and below the valve and spread upon the inner

surface thereof. As before explained the differences of diameter between the valve, the cylinder and the head, are so slight that only minute films of oil may occupy the spaces. These are in fact capillary spaces and while the oil will freely work into and occupy the spaces, due to the rotation of the valve within the inclosing walls, the oil cannot easily be discharged from the spaces by either internal or external pressure. The films of oil constitute fluid packings for the joints. This fact makes it possible to adequately lubricate the valves and inclosing walls without danger of gas leakage from or to the cylinders at moments of compression, combustion and vacuum therein. The balancing of the valve as before explained further eases the movement of the valve and it is clear that it is practically impossible for any surface of the valve to engage any opposed surface upon the head or cylinder except through the medium of this minute film of oil which envelops the valve. In consequence the valve and valve seats will operate indefinitely without perceptible wear. Shallow vertical collecting grooves K^4 may be formed in the valves K at the "following" side of respective ports K^2 , as shown in Figs. 1 and 4 and to expedite the distribution of oil within the valve chambers or cavities, I preferably provide the walls thereof with shallow oil grooves. The grooves a^x in the cylinder walls are so inclined that they tend to elevate the oil from the gear openings AN , whereas the grooves J^x in the surfaces of the heads may tend to force the oil downward. As shown in Fig. 3 the upper edge of each valve K is preferably provided with an annular oil groove K^x for an accumulation of oil, to better distribute the oil upon the inner surface of the valve. Very little of the oil thus supplied to the valve is wiped off at the ports, the greater part returning to the trough through the openings AN . It will thus be seen that the valves, the valve cavities and the valve gears constitute an oil circulating system which insures the positive lubrication of these parts at all times. The tight joint before alluded to, between the lower end of the head J and the cylinder prevents leakage of valve oil into the cylinder, a feature which is of distinct advantage.

As before explained the water space C within the cylinder casting extends to the top of the cylinders and cooling water is therefore supplied to all of the upper parts of the cylinders except those portions or areas which are occupied by the admission and exhaust passages A^d , A^x , and the gear openings AN . The cooling of the outer walls of the valve cavities and the outer portions of the valves is thus insured. Each head J contains a water space J^v . The

water is supplied and discharged through pipes J^p , two of which are provided for each head. The top of the head contains a depression to admit, and afford easy access to, the firing plug M . The space J^v occupies nearly the whole of the head, only thin walls remaining; the exceptions being the space occupied by the passages JA^d , JE and JB . As before described, the head is deeper than the valve K , extending both above and below the same. The water space is likewise deep, its bottom being preferably below the level of the valve K and the water rising therein to a level above the top edge of the valve. In other words, the cooling surface of the valve wall of the head is practically coextensive with the valve and the maintenance of the valve at a low temperature is positively insured. It is not material whether the valve enveloping walls are cooled by water or by air, or by some other medium; the important point is that the valves and the inclosing walls are so formed and related that they are quite separate from the hotter portions of the cylinder and head and are fully exposed to the cooling medium.

The operation of the engine is according to the well known four-cycle principle and will be clearly understood from the foregoing detailed description of the operation of its several related parts.

The valve construction in itself and the combination of parts, including the shaft N , for actuating the valves, comprise the subject matters, respectively, of my co-pending applications Serial Nos. 659,204, and 667,764, and are not specifically claimed herein.

Having thus described my invention, claim as new and desire to secure by Letters Patent:

1. In an internal combustion engine, a cylinder and a piston therein in combination with a cylinder head fixed in the end of said cylinder, the inner and outer ends of said head being tightly jointed to said cylinder throughout their respective circumferences, the intermediate portion of said head being of less diameter than the adjacent portion of the cylinder and concentric therewith, an annular valve cavity being thereby formed between said ends of the head, one side of said head and cylinder containing admission and exhaust ports which open into said cavity, an annular valve of slightly greater diameter than the head and of slightly less diameter than said adjacent portion of the cylinder and occupying said cavity, said valve containing a port positioned to register with aforesaid ports, said head containing a balancing port approximately opposite the first mentioned ports, means for supplying oil to said cavity

and means for rotating said valve in said cavity in time with the movements of said piston.

2. In an internal combustion engine, a cylinder and a piston therein, in combination with a head concentric with and fixed in the end of the said cylinder, said head having inner and outer ends which make complete annular tight joints with the cylinder, the cylinder and head having corresponding admission and exhaust ports in one side thereof between said joints, an annular valve of slightly greater diameter than said head and of slightly less diameter than the cylinder longitudinally fixed between said head and cylinder and between said joints and having two diametrically opposite ports adapted to register with the aforesaid ports, the distance between the ports in the cylinder approximating the width of each port in said valve, a balancing port in said head approximately opposite the first mentioned ports in position to register with the ports in the valve, means for supplying oil to said valve, and means for rotating said valve once during every eight strokes of said piston.

3. In an internal combustion engine, a cylinder and a piston therein, in combination with a head concentric with and removably fixed in the end of said cylinder, said head having inner and outer ends which make complete annular joints with the cylinder, the cylinder and head having corresponding admission and exhaust ports in one side thereof between said joints, an annular valve of slightly greater diameter than said head and of slightly less diameter than the cylinder longitudinally fixed between the cylinder and head and between said joints and having a port adapted to register with the aforesaid ports, the distance between the ports in the cylinder approximating the width of said port in said valve, a balancing port in said head approximately opposite the first mentioned ports, in position to register with the port in the valve, and of slightly less area than the combined area of the first mentioned ports, means for supplying oil to said valve, and means for rotating said valve in time with the movements of said piston.

4. In an internal combustion engine, a cylinder and a piston therein, in combination with a cylinder head removably fixed in the end of said cylinder, the inner and outer ends of said head making complete annular oil and pressure tight joints with said cylinder, the intermediate portion of said head being of less diameter than the adjacent portion of the cylinder and concentric therewith, an annular valve cavity being thereby formed between said ends of the head, one side of said head and cyl-

inder containing admission and exhaust ports which open into said cavity, an annular valve of slightly greater diameter than the head and of slightly less diameter than said adjacent portion of the cylinder and occupying said cavity, said valve containing one or more ports positioned to register with aforesaid ports, said head containing a balancing port approximately opposite the first mentioned ports and positioned to register with the port in the valve, an opening in the cylinder adjacent the said balancing port, valve operating means positioned in said opening and means for supplying oil to said operating means and valve.

5. In an internal combustion engine, a cylinder and a piston therein, in combination with a cylinder head removably fixed in the end of said cylinder, the inner and outer ends of said head being in complete circumferential jointure with said cylinder, the intermediate portion of said head being of less diameter than the adjacent portion of the cylinder and concentric therewith, an annular valve cavity being thereby formed between said ends of the head, one side of said head and cylinder containing admission and exhaust ports which open into said cavity, an annular valve of slightly greater diameter than the head and of slightly less diameter than said adjacent portion of the cylinder and occupying said cavity, said valve containing two approximately opposite ports positioned to register with aforesaid ports, said head containing a balancing port approximately opposite the first mentioned ports and positioned to register with the ports in the valve, an opening in that side of the cylinder which is adjacent to said balancing port, valve operating means positioned in said opening, means for supplying oil to said operating means and valve and a driving connection between said piston and said operating means.

6. In an internal combustion engine, a cylinder and a piston therein, in combination with a head concentric with and fixed in the end of said cylinder, said head having inner and outer ends which make tight joints with the cylinder throughout their respective circumferences, the cylinder and head having corresponding admission and exhaust ports in one side thereof between said joints, an annular valve of slightly greater diameter than said head and of slightly less diameter than the cylinder longitudinally fixed between the cylinder and head and between said joints and having two diametrically opposite ports adapted to register with the aforesaid ports, the distance between the ports in the cylinder approximating the width of each port in said valve, a balancing port in said head approximately opposite the first mentioned

- ports, means for supplying oil to said valve, and means for rotating said valve once during every eight strokes of said piston.
7. In an internal combustion engine, a cylinder and a piston therein, in combination with a head concentric with and fixed in the end of said cylinder, said head having inner and outer ends which throughout their respective circumferences make tight joints with the cylinder, the cylinder and head having corresponding admission and exhaust ports in one side thereof between said joints, an annular valve of slightly greater diameter than said head and of slightly less diameter than the cylinder longitudinally fixed between said cylinder and head and between said joints and having a port adapted to register with the aforesaid ports, the distance between the ports in the cylinder approximating the width of said port in said valve, a balancing port in said head approximately opposite the first mentioned ports and of slightly less area than the combined area thereof, means for supplying oil to said valve, and means for operating said valve in time with the movements of said piston.
8. In an internal combustion engine, a cylinder and a piston therein, in combination with a cylinder head fixed in the end of said cylinder, the inner and outer ends of said head being tightly jointed to said cylinder throughout their respective circumferences, the intermediate portion of said head being of less diameter than the adjacent portion of the cylinder and concentric therewith, an annular valve cavity being thereby formed between said ends of the head and closed at top and bottom, one side of said head and cylinder containing admission and exhaust ports which open into said cavity, an annular valve of slightly greater diameter than the head and of slightly less diameter than said adjacent portion of the cylinder and occupying said cavity, said valve containing spaced ports to successively register with aforesaid ports, said head containing a balancing port opening against said valve approximately opposite the first mentioned ports, an opening in the cylinder adjacent the said balancing port, valve operating means positioned in said opening and means for supplying oil to said operating means and valve.
9. In an internal combustion engine, a cylinder and a piston therein, in combination with a cylinder head fixed in the end of said cylinder, the inner and outer ends of said head being tightly jointed to said cylinder throughout their respective circumferences, the intermediate portion of said head being of less diameter than the adjacent portion of the cylinder and concentric therewith an annular valve cavity closed at its ends being thereby formed between said ends of the head, one side of said head and cylinder containing admission and exhaust ports which open into said cavity, an annular valve of slightly greater diameter than the head and of slightly less diameter than said adjacent portion of the cylinder and occupying said cavity, said valve containing two approximately opposite ports positioned to register with aforesaid ports, said head containing a balancing port approximately opposite the first mentioned ports, an opening in that side of the cylinder which is adjacent to said balancing port, valve operating means positioned in said opening, means for supplying oil to said operating means and valve and a driving connection between said piston and said operating means.
10. In an internal combustion engine, a single block containing a plurality of suitably cooled cylinder bores, in combination with a single piece suitably cooled head in each said bore, a single piece annular sleeve valve concentric with and interposed between each head and its bore, each said head being jointed to the cylinder bore above and below its respective valve, said cylinders, valves and heads each having a complement of gas flow ports, and each head containing a balancing port opening against its valve opposite the gas flow ports, an opening in the side of each cylinder bore, a valve operating member acting upon all said valves through said openings, pistons in said bores and a driving device for said member, operated by the movement of said pistons.
11. In an internal combustion engine, a one piece cylinder containing a cylinder bore comprising a piston containing portion and a head containing portion, in combination with a one-piece ported sleeve valve concentric with and fitting the head containing portion of said bore, a one-piece head concentric with and fitting said valve, the ends of said head being jointed to the cylinder above and below respective ends of said valve, said cylinder and head containing admission and exhaust ports to register with the port in the valve, means for rotating said valve and said head containing a balancing port opening against the inner side of said valve opposite said admission and exhaust ports.
12. In an internal combustion engine, a one-piece cylinder containing a cylinder bore comprising a piston containing portion and a head containing portion, in combination with a one-piece plurally ported sleeve valve concentric with and fitting the head containing portion of said bore, a one-piece head concentric with and fitting said valve, the ends of said head being jointed to the cylinder above and below respective ends of

said valve, said cylinder and head containing admission and exhaust ports to register with successive ports in the valve, said head containing a balancing port opening against
5 the inner periphery of said valve approximately opposite the ports in the cylinder and head, and means for rotating said valve.

In testimony whereof, I have hereunto set my hand, this 8th day of November, 1911, in the presence of two subscribing witnesses.

EDWARD H. BELDEN.
